UNITED STATES PATENT OFFICE.

EDWIN HENDRY BENNERS, OF ELIZABETH, NEW JERSEY.

BOLSTER.

No. 799,295.

Specification of Letters Patent.

Patented Sept. 12, 1905.

Application filed November 28, 1903. Serial No. 183,067.

To all whom it may concern:

Be it known that I, EDWIN HENDRY BENNERS, a resident of Elizabeth, in the county of Union and State of New Jersey, have invented certain new and useful Improvements in Bolsters; and I do hereby declare the following to be a full, clear, and exact description of the invention, such as will enable others skilled in the art to which it appertains to make and use the same.

My invention relates to an improved truck-bolster, the object of the invention being to provide a cast-steel bolster which will embody maximum strength with minimum weight; and it consists in certain novel features of construction and combinations and arrangements of parts, as will be more fully hereinafter described, and pointed out in the claims.

In the accompanying drawings, Figure 1 is a top plan view illustrating my improvements. Fig. 2 is a view in side elevation; and Figs. 3, 4, and 5 are views on the lines $x x$, $y y$, and $z z$, respectively, of Fig. 1.

My improved bolster consists of one integral casting forming in the main top member 2, horizontal throughout the greater portion of its length, bottom member 3, of less width than top plate 2 and inclining or curving upward from its center to its ends and connected with top plate 2 by inclined open-work webs 4, the cross-section of the bolster thus being tapering from its top to its bottom. The top and bottom plates 2 3 and side webs 4 all merge into slightly-enlarged bolster ends, having recesses or pockets 5 in their opposite sides for the column-bearings, the upper plate having recesses or cut-out portions 6 in its ends and the lower plate made with longitudinal and lateral strengthening-ribs 7.

The top plate 2 has a raised ring or center bearing 8 and end bearings 9, and a hollow bearing-post 10 is made integral with top plate 2 and is located in the center of center bearing 8.

By constructing my improvements as above explained the tapering formation of

the bolster in cross-section, as seen most clearly in the sectional views, gives to the bolster great strength and durability to withstand all strains thereon at the same time having the bolster of minimum weight and neat and attractive in appearance.

While I have described the side connecting webs 4 as inclined, as a matter of fact the upper portions of said side webs, which form, in effect, depending aprons 11 from the side edges of top plate 2, are disposed vertically and are of greater thickness than the main or larger portions of said side webs, and while I prefer this particular construction of bolster a great many changes might be made in the general form and arrangement of the several parts without departing from my invention. Hence I do not restrict myself to the precise details set forth, but consider myself at liberty to make such slight changes and alterations as fairly fall within the spirit and scope of my invention.

Having fully described my invention, what I claim as new, and desire to secure by Letters Patent, is—

1. A bolster comprising a top plate, a narrower bottom plate and inclined side webs connecting them, said side webs being approximately straight from the top to the bottom plates.

2. A bolster comprising a top plate, a narrower bottom plate and inclined open-work webs connecting said plates, said webs being approximately straight from the top to the bottom plates.

3. A cast-metal bolster, comprising a top plate, a bottom plate of less width than the top plate, and approximately straight side webs connecting the longitudinal edges of the top and bottom plates.

In testimony whereof I have signed this specification in the presence of two subscribing witnesses.

EDWIN HENDRY BENNERS.
